UNITED STATES PATENT OFFICE.

FREDERICK G. JAHN, OF BROOKLYN, NEW YORK, ASSIGNOR TO INTERNATIONAL POSTAL SUPPLY COMPANY, A CORPORATION OF NEW YORK.

TRANSFER OR COUPON COLLECTOR AND COUNTER.

1,232,319.

Specification of Letters Patent.

Patented July 3, 1917.

Application filed June 16, 1914. Serial No. 845,354.

To all whom it may concern:

Be it known that I, FREDERICK G. JAHN, a citizen of the United States, and a resident of Brooklyn, in the county of Kings 5 and State of New York, have invented certain new and useful Transfer or Coupon Collectors and Counters, of which the following is a specification.

This invention has the primary purpose 10 of providing a machine for counting transfers. Street railways are troubled with keeping track of the transfers collected from the passengers. Passengers generally enter cars in crowds at transfer points, and 15 the conductor has to collect the transfers rapidly, particularly in the present type of "pay as you enter" cars. The street car company loses by the fact that the subsequent counting of the transfers by the conductors may not be accurate, either through 20 intention or accident. It will be understood that the transfers are necessarily of cheap limp paper, and further that they are quite often crumpled, wet, folded or torn 25 when handed to the conductor, making it difficult even for a careful or skilled person to correctly count the same. With conductors, and under the conditions of street car traffic, it is found that this count is very 30 inaccurate, even with the more careful and scrupulous men. It is therefore impossible to check up frauds practised upon the company by the miscounting of transfers. Moreover for the very purpose of checking 35 the above human errors, it is evidently necessary to have girls subsequently go over the count, which is an item of considerable expense and trouble. Therefore it is strongly desirable, and a thing long sought 40 for by the street car companies, to provide some appliance which shall relieve the conductors of the trouble and vexation of counting stacks of wet, limp or torn and crumpled transfers, also relieving them of 45 the blame of unintentional mistakes, further precluding the possibility of fraudulent counting by dishonest conductors, and avoiding the expense of the corps of girls, who now count the transfers as a check on the 50 conductors. It is the primary purpose of the present invention to provide such a machine. Of course, the machine is capable of other uses, and in some other such uses certain requisites of strength, and proof against 55 tampering or unintentional or accidental

misuse will not be required, or required to the same extent. For example, in counting bills or tickets received at a theater or the like, and many sorts of receipts or checks of commercial practices, it may be possible 60 to dispense with a portion of the precautionary and other special features herein employed. In other words, the present invention as described in the practical embodiment herein set forth includes a variety 65 of features, the advantages of which will be apparent, but many of the features and points are to be differentiated as minor and subsidiary, from what is primary and essential. Such modifications throughout, 70 as fulfil the same inherent purposes, will also suggest themselves.

In the drawings:—

Figure 1 is a top view of a transfer counter embodying the principles of this invention. 75

Fig. 2 is a front view of the same with the casing partly broken away.

Fig. 3 is a sectional view on the line III—III of Fig. 2. 80

Fig. 4 is a side view of the gripper drum.

Fig. 5 is an end view of the same.

Fig. 6 is a similar view partly in section with some of the parts removed for clearness, and also showing part of the "Geneva 85 stop" wheel.

Fig. 7 is a similar view showing a position of the parts when a transfer or the like is gripped.

Fig. 9 is a longitudinal sectional view through the drum head showing the grippers and secondary levers.

Fig. 10 is a side view of the main operating lever for the gripper drum. 95

Fig. 11 is a detail sectional view of the same.

Fig. 12 is an end view showing the counter and a train of actuating gears 100 therefor.

Fig. 13 is a view of a main operating lever for the gripper drum having a slightly modified construction.

Fig. 14 is a sectional view of the same. 105

Fig. 15 is another modification showing a counter on the side of a box or casing instead of at the top.

Fig. 16 shows same form outside of box.

Gripper drum.—Constructions embody- 110

ing the invention will include a gripper drum 10 or carrier adapted to be intermittently rotated or moved from a transfer receiving position to a transfer discharging position. Transfer grippers, as 11, will be supported on this carrier. The action of the grippers and carriers is such as to afford a register or actuation of a registering mechanism when a transfer is engaged by the carrier, but on the other hand there will be a positive and definitely controlled omission of such registering action when a transfer is not being engaged and carried from the receiving to the delivery position.

15 Constructions embodying the invention will also include a stacker 12 by which transfers or the like are neatly piled in bundles or packages, in which condition they may be removed from the machine. This removal will however only be possible by an authorized person.

In the best constructions embodying the invention the motion of the gripper carrier is controlled by a lip 17 of a hopper mouth 13 through which the transfers are fed into the machine. The action is a prompt, positive, easy and definite displacement of the gripper carrier when the lip of the hopper is manually swung outward. It will also be seen that provision is made for having the apparatus "fool proof," and also proof against wilful tampering. For example, provision is made against the possibility of feeding in a transfer in any way without giving a count. The count will be given whether the transfer is long or short or torn or folded. Also the machine will in no case give any count when a transfer is not inserted. The result is that a count is made for all the passengers giving up transfers. The convenient insertion of the transfers into the hopper mouth of the machine makes it possible to inforce the prompt and immediate registering of such transfers, as a matter of discipline, in other words the insertion of the transfers into the hopper, individually as they are collected, can be made a matter as inforceable as is the present practice of depositing the coins collected into a hopper. Provision is also made for such a prompt gripping of the transfers as will insure their being drawn into the machine even though carelessly deposited in the hopper 13, or perhaps held back somewhat by a wet condition or the accidental holding back by the conductor's hand in manipulating the machine.

In the best constructions embodying the invention the mechanism will be housed in a compact casing 15, having a depressed hopper mouth 13. The front lip 17 of the hopper mouth can be displaced by a pull forwardly as shown by dotted lines 17' in Figs. 3 and 13. For this purpose this lip 17 is conveniently pivoted, and as illustrated in

Figs. 3 and 13 it is fixed to a shaft or axle 18 which extends across the machine adjacent to the front side of the gripper drum 10. As shown clearly in Fig. 3, the hopper or receiving mouth presents a passage substantially tangential to the periphery of the drum. This shaft or axle 18 may be termed an actuator shaft.

A fixed frame bar 19 serves the threefold purpose of closing any gap in the casing 15 at the base of the lip 17, also affording a strong back stop, which may be covered with felt 20 to softly limit the downward movement of the lip or actuator 17, and also constituting a support for a finger plate 21 which has upwardly curved fingers 22 directing the transfers into the bite of the grippers. For this purpose the fingers 22 alternate with the grippers 11, as clearly shown in Fig. 2. In other words, the fingers 22 project so far toward the axis of the gripper carrier that they would interfere with the grippers, except for the fact that they are alternated with the grippers so as to be out of the path of the rotation of the grippers. It is particularly to be noted that the strength of the bar 19 is adequate to arrest the forward pull of the lip 17 even although the actuation thereof be very forcible. On the other hand, such excessive force will not find an opportunity to act on any other part of the mechanism, particularly on the operating parts.

The drum 10 already referred to, which in the embodiment illustrated constitutes a rotating carrier for the transfers, is substantially a multiple disk or skeleton cylinder on a shaft or axis 24 having bearings, preferably ball bearings 25, in the end plates of the casing 15. The gripper carrier is preferably of skeleton formation, being practically composed of a series of thin plates or disks 26, held apart by spacers 27. At the ends of the gripper drum illustrated are strong plates 28 which may be termed gripper drum heads. One of the principal purposes of the skeleton formation just described is to afford a free movement of the grippers, not only outward into open position to receive a transfer, but also into closed position to grip the transfer, and into a position still further inward, corresponding to when a transfer is not present. A series of a considerable number of grippers makes the action positive even when the transfers are folded and limp or wet, or when a very short transfer or coupon from a transfer, is collected.

In order to well accomplish these various functions the grippers 11 are evenly mounted in several extensive series on a plurality of gripper axles 30 spaced around the gripper drum. The grippers alternate in position with the gripper drum disks 26 as clearly shown in Fig. 2. On one of the 130

heads 28 of the gripper drum a mechanism is conveniently provided for operating the grippers. This mechanism may be generally termed the gripper operating mechanism.

Means for operating the grippers.—An efficient construction for operating the grippers consists of a lever arm 32 fixed to each gripper axle 30, the arm 32 being of double plate construction in the interest of strength and durability, and having a cam roll 33 firmly pivoted thereto on a fixed stud 35 joining such double plates which constitute the arm 32. This cam roll 33 engages a cam 34 (see Figs. 5, 6 and 7), which for present purposes may be considered a stationary or fixed cam secured to one of the side plates of the case of the main frame 15 (see particularly Fig. 8). It will be seen from Figs. 6 and 7 that the rotation of the gripper drum in the direction of the arrow causes the cam roll 33 which is spring pressed inward by spring 43, to move toward and from the axis of the gripper drum, as this cam roll 33 rides up and down around the cam 34. In both Figs. 6 and 7 the gripper has just snapped inward from its open or transfer receiving position. In Fig. 6, however, the gripper has closed farther inward than in Fig. 7 because no transfer is in position to be engaged in Fig. 6, while a transfer is held under the gripper in Fig. 7, thereby preventing the gripper from closing in as far as in Fig. 6. This difference in the position of the grippers when a transfer is being engaged, and when no transfer is present to be engaged, constitutes a form of means for affording a registration only when a transfer is being fed.

This may be advantageously taken up under a separate head.

The counter studs on the gripper carrier.—In the practical construction illustrated, the position of the grippers 11 acts to position a counter stud 40 at a different radial position out on the gripper drum 10 in one case from that in another case. In order to get sufficient displacement of the stud 40, a multiplying leverage is advantageous, and the gripper operating arm 32 is shown with an extension 36 engaging a tappet 37 of a secondary lever 38 which is spring controlled, by spring 39, to normally assume the position shown in Fig. 7. This secondary lever 38 carries the counter stud 40 in this construction and is conveniently made with a double plate construction for strength, with a folded over integral back plate 41 which engages a neighboring operating gripper arm 32 so as to constitute a stop. This fixes the spring controlled position of the secondary lever and counter stud 40 as shown in Fig. 7. On the other hand, the engagement of the gripper operating arm extension 36 with the tappet 37 dis-

places this secondary lever 38 to the extent shown in Fig. 6 where it and its counter stud 40 have a different position radially outward from the center or axis of the gripper drum than in Fig. 7. The grippers themselves are of course constrained to move inward into position to grip the transfers by means of the springs 43 already mentioned. These springs 43 conveniently run from the tie rods 27 as shown in Fig. 5 to an ear 49 on the gripper operating arms 32. It is obvious that the spring 43 must be strong enough to overpower the spring 39 of the secondary lever. The counter stud 40 travels in a path controlled as just described as to radius, being otherwise borne in the direction of the arrow in Fig. 7 by the rotation of the spring drum. This counter stud will therefore engage the notches of a Geneva stop wheel 50 or similar device, in case its radial position is such as to permit this, which is the case when a transfer is present, as is shown in Fig. 7. The Geneva stop wheel is of course normally locked by its engagement with the drum head 28. The drum head will be cut away at 51, beneath the pin or stud 40, to permit the unlocking of the Geneva stop wheel and the actuation by the counter stud 40. Referring particularly to Figs. 7 and 15, it will be seen that the pin 40 at the instant of engaging the Geneva wheel 50 has a force put thereon tending to strain the arm 38 into a fixed position with the stud 41 against the abutment 30. This has the effect of virtually locking said stud 40 in place while the Geneva wheel is being actuated. In other words, the only possible movement of the stud 40 is directly against its engagement with the said Geneva wheel, which virtually locks it in place during such engagement. The arc or angle through which the transfer is carried includes the position where the counter stud 40 is passing the Geneva stop wheel or like device, and in the form illustrated in the drawings this angle or arc is about 120 degrees. Fig. 9 illustrates a practical detail of the prior bearing for the secondary lever 38 which is a sleeve 44 fixed on the tie rod 27 by a nut 45.

Instant gripper closure.—Mention has been made of the cam 34 which controls the grippers and thereby fixes the arc or angle of movement through which the transfers are carried. It will be evident that when the cam rollers 33 ride up on a high part of the cam 34 that the grippers 11 are open, but on the other hand, when the cam rollers 33 pass opposite a cut away part of the cam 34, the grippers close inward under the influence of the springs 43. It is very desirable that the grippers move in promptly, that is to say with a snap. This is desirable in that it permits the grippers to engage the transfer more forcibly, as by impelling

105

110

115

120

125

130

the same more or less with any teeth or serrated edges as desired. Aside from this it permits the transfers to start in motion very promptly and positively as obviously the 5 grippers must be free or wide open when the transfer is inserted in order to enable its convenient insertion, and thereafter it is important that the grippers get closed as quickly and speedily as possible, since otherwise time and motion is lost before the grippers are fully closed. During this period 10 the transfer may slip from its original position where it was to be engaged, and in any event it is important in this mechanism 15 not to have any time and motion lost for there is little of either to spare in such a manipulation as has been described in the preamble to this specification. Therefore, the cam 34 is made composite in a practical 20 construction embodying the present invention, having two parts 34^a and 34^b, the part 34^a being actually fixed in the machine as shown in Fig. 8. The part 34^b, however, is capable of slight backward reaction within 25 the limits of the notch 55. The pin 56 which projects from the cam part 34^b is engaged by a spring 57' normally impelling this cam part 34^b into the position of Fig. 5. The instant that the cam roller 33 begins to 30 move inward, however, the cam part 34^b is kicked, so to speak, by the reaction out of the way so that the cam roller 33 moves inward sharply and suddenly as soon as it is started, as if there were a sharp shoulder 35 passing off a sharp corner on the cam, in other words, by a practically instantaneous movement. The closing of the grippers with a snap in this way from their fully open position to their fully closed position is obviously an important and desirable practical 40 feature for the reasons mentioned.

The counter.—A feature of improvement consists in the means by which the register is positively locked at all times, except when 45 being actuated, and is actuated in such a way as to prevent any mistaken count due to any accidental or wilful uses or manipulation to which the machine may be exposed. Mention has been made of the initial Geneva 50 stop wheel 50 or like device, of a counter or recorder mechanism of any suitable or desirable character. For convenience the Geneva stop wheel 50 may carry a gear 60 which is the first of a train of gears 61, 62, 55 63 and 64, the gear 64 being on the axle of a usual counter 65, the details of which need not be illustrated since counters of general character illustrated are well known in mechanics. It is desirable to have duplicate 60 counters, one capable of being reset, while the other shows the aggregate total at all times. Duplicate counters of this kind are common for use in various arts. In place of a counter, it is of course possible to use other 65 registering or indicating devices. An al-

ternative style of counter is illustrated in Fig. 15, embodying three numeral disks 50', 58', 59' mutually interconnected by Geneva stop gears 50, 58 and 59 of ordinary form.

The stacker.—It has been shown that the transfers are engaged by the grippers and carried by the gripper carrier for a certain distance, and as illustrated this distance is a third of a revolution on the gripper drum shown. At the end of this movement the grippers open, as described, by reason of their cam rolls 33 riding on to a high part of the cam 34. At this instant transfers are being deposited in substantially the position of Fig. 3.

In the best constructions embodying the invention transfers are collected into a stack or bundle on a removable shelf or suitable box, such shelf, where employed, having provision for gradually retreating as the transfers accumulate. As illustrated the shelf 67 is located directly against the gripper drum 10, and is normally pressed there against by a pair of spiral springs 68. The shelf 67 is guided by upstanding guides 69 and a back wall or stop 70, which has overhanging tongues 71, which finally arrest the transfers when properly located on the shelf 67. The slight friction between the disks 26 and the top transfer on the shelf 67 insures the neat piling up or positioning of the transfers against the back stop 70. As the transfers accumulate the shelf 67 automatically descends. At suitable times the entire package of transfers may be taken out. A handle 72 affords an easy means for pulling out the shelf or box and its entire associated parts, it being understood that a suitable door 73 has previously been unlocked and opened.

The movements of the gripper carrier.—The fact that the gripper carrier has certain movements imparted thereto, and the further fact that the usual prime actuator or mover consists of the lip 17 of the hopper mouth 13, has already been pointed out as characteristic of best embodiments of this invention. The means for transmitting the motion from one to the other of these elements should insure a number of conditions.

First, the gripper carrier should be locked in its normal position, second, it should be unlocked and started into rotation without possibility of retreating or doing anything less than completing the movement thus started. Third, the motion of the gripper carrier should be positively stopped when its proper movement has been completed, fourth, it should be relocked in its new position. Fifth, it should not be possible by any unusual manipulation of the original actuator to cause either any greater or any less movement than this, at least so far as the ultimate result of producing a registration or affording an opportunity for feed-

80

85

90

95

100

105

110

115

120

125

130

ing a following transfer is concerned. Sixth, all of the movements shall be at all times unable to oppose any direct opposition to a free movement of the original actuator, which otherwise would strain the more delicate parts by applying an excessive force to them. Seventh, the transmission of motion from the actuator to the gripper carrier should be very efficient at all stages, since this strains the delicate mechanism less, and also makes the movement of the original actuator easier, further securing a more equal and freer movement of the gripper carrier without any jerks or pauses.

These various purposes or objects are attained by the mechanism practically illustrated in Figs. 3 and 10; and also 13 and 14. Upon the axle 18 of the original actuator, serving in this case as the actuator shaft, is secured an arm 80 having reversed hooks 81 and 82, the hook 81 having a normal position as shown in Figs. 3 and 10. It will be observed that the hook 82 has a notch 83 at its base which receives a tooth or stud 84^a projecting from the drum head 28 at this end of the machine. The preceding tooth or stud 84^c of the series around the drum head is just clear of the hook 81 at this time. A feeding pawl 85 depends from an extremity 95 of the actuator plate 80 and has a hooked end 86 (see Fig. 10) engaging over another of the studs 84, in this case the third and remaining stud 84^b of the series, there being three sets of grippers on the gripper carrying drum. In addition to the features thus far considered the hook 82 has further an arcuate extension 87, which is sufficiently projecting to always oppose a barrier to any return movement of the adjacent stud 84^c. This extension 87, however, is terminated at such a point as to permit the passage of the third stud 84^b when the rotation of the gripper drum has been sufficient to nearly move the stud 84^b to the position shown occupied by the stud 84^a. At this time the hook 81 has been projected to such an extent as to independently prevent any reverse movement of the gripper drum, and also offer a positive stop to arrest the stud 84^a which has been by this time turned to the position now shown occupied by the stud 84^c. It will further be observed that the motion of the actuator plate 80 is pivotal about an axis so close to the gripper drum as to give an easy turning effect thereto especially when the movement is imparted through a comparatively long link such as the feeding pawl 85. Moreover, the position of the axis of oscillation of the actuator plate 80 is such as to make the pull on the feeding pawl 80 as nearly in a direct line with the motion of the parts connected thereto at the starting end as possible. Due to these various fea-

tures the rotation of the gripper drum through a third of a rotation is readily secured by the oscillation of the lip 17 as already described, and the further functions pointed out are also secured in an obvious manner. An additional locking pawl 88, to prevent rearward rotation of the gripper drum, may be added if desired. A further feature which may be mentioned consists in the fact that the feeding pawl 86 (see Fig. 10) has an extension 90 which contacts with the bearing 25, or some equivalent abutment, when the feeding pawl is descending. This action thrusts the feeding pawl over the stud 84^b so as to engage the same instead of passing inside the stud 84^b and failing to engage the same. This feature is merely incidental to the carrying out of the purposes first above described in the manner mentioned.

The mechanism just described is also illustrated in Fig. 13 which however, has one additional feature. According to Fig. 13 the feeding pawl 85 has a lateral projection 92 which swings upward into contact with an abutment 93, thereby giving the feeding pawl a certain inward directing force which accords with the somewhat altered direction of movement of the stud 84^b at this time. This gives a more advantageous tractive or pulling effect on such stud. As indicated in Fig. 11 the feeding pawl 85 is conveniently pivoted to the actuator plate 80 by having a bent-over ear 94 which embraces the extremity 95 of such plate 80. A pair of hardened washers 96 are firmly riveted through at this extremity 95 after the feeding pawl 85 has been properly located, thereby fixing all the parts permanently in pivotal relation, and securing a hard and good bearing surface as well.

General operation.—The general operation of the above construction, is briefly to drop the transfers, individually as collected, into the hopper mouth 13, and then pull upon the lip 17 which through the actuator plate 80 lifts the feeding pawl 85, and thereby pulls the tooth or stud 84 upward until the drum has been rotated through a third of a revolution. As the drum rotates the grippers 11 first snap closed by reason of their cam rolls 33 dropping into a low part of the fixed cam 34. Subsequently, after a third of a revolution, the grippers open by reason of their cam rolls 33 riding onto a high part of this same cam 34, or an associated part thereof. As the grippers release the transfer the latter is pushed snugly into place on the receiving shelf or stacker 67 by the frictional engagement of the gripper drum, which also exerts a certain camming down effect on the pile and assists the uniform stacking of the transfers. The transfers are subsequently removed by drawing out the entire stacker which has

the tongues 71 to hold the transfers in a unit pile while being so withdrawn. In this way they may be conveniently dropped into envelopes or otherwise banded into a bundle 5 in the most convenient way. The movement of the grippers in engaging the transfers influences the position of a counter-stud 40 on the gripper drum to such an extent that in case a transfer has been grasped 10 this stud engages and actuates the Geneva wheel 10. If, on the other hand, no transfer is in place, the inward movement of the grippers is excessive and results in such a positioning of the counter-stud 40 that the Geneva wheel 50 is not engaged, and no count 15 results. Thus the transfers are accurately counted as well as stacked and collected. The additional features of operation by which special effects are secured, such as the 20 precise control of the gripper drum in this movement, the locking and unlocking thereof, and the proof against tampering or misuse have already been alluded to in taking up the various mechanisms in the earlier 25 part of the description, and need not be here repeated.

What is claimed is:—

1. In a machine of the class described, a gripper carrier, an actuator therefor, a casing 30 having a mouth adjacent to said actuator and delivering in proximity to said carrier, a counter, and means connected to the carrier for locking the counter against movement during idle or non-feeding movements 35 of said gripper carrier.

2. In a machine of the class described, a carrier, an actuator therefor, grippers on 40 said carrier, a casing having a mouth adjacent to said actuator and delivering in proximity to said carrier, a counter, and means operated by a normal closing movement of the grippers for permitting an actuation of 45 said counter.

3. In a machine of the class described, a 45 drum, an actuator for said drum, a casing having a mouth adjacent to said actuator and delivering in proximity to said drum, a counter actuated by the rotation of said drum, and means for permitting an actuation 50 of the counter during feeding movements of the drum.

4. In a machine of the class described, a 55 drum, an actuator therefor, grippers on said drum, a casing having a mouth in proximity to said actuator and delivering to said drum, receiving means to which said drum delivers, means operated by the rotation of the drum for opening and closing said grippers, a counter, and means for permitting an actuation 60 of said counter when the grippers have a normal closing movement.

5. In a machine of the class described, a 65 drum, a casing having a hopper delivering to said drum, a lip on the hopper for rotat-

ing said drum, grippers on the drum opened 65 and closed by the rotation of the drum, a counter actuated by the rotation of the drum, receiving means to which the drum delivers, and means for permitting an actuation of said counter when the grippers have 70 a normal closing movement.

6. In a machine of the class described, a drum comprising a series of disks, grippers closing into the space between said disks, a counter actuated by the rotation of said 75 drum, and means actuated by a normal movement of the grippers between said disks for permitting an actuation of said counter.

7. In a machine of the class described, a carrier adapted to receive and advance an 80 article, a counter adapted to be actuated by said carrier, and means permitting actuation of said counter during feeding movements of the carrier, said means being rendered operative by the presence of the article 85 being advanced by the carrier.

8. In a machine of the class described, a gripper carrier, a casing having a receiving mouth, a lip movable on said mouth, means for moving said carrier from said lip, a 90 counter stud on the casing, means on the carrier for positioning said stud at different radial positions, and counting mechanism in the path of said stud adapted to be actuated in certain radial positions thereof. 95

9. In a machine of the class described, a gripper carrier, a casing having a receiving mouth, means for moving said carrier, a counter stud rocking on said carrier, said counter stud having a limited outward rocking 100 movement, and a counter located to be in a path where it may be engaged by said counter stud at the limit of its rocking movement.

10. In a machine of the class described, a carrier, a casing having a receiving mouth, a movable lip on said mouth, means for moving said carrier by said lip, grippers upon said carrier movable in a closing direction beyond normal gripping position, a 110 counter, and a device for actuating said counter by said carrier, and means for automatically moving said device to inoperative position when the grippers move in a closing direction beyond normal gripping 115 position.

11. In a machine of the class described, a gripper carrier, a casing having a receiving mouth, a lip movable on said mouth, means for moving said carrier from said lip, a 120 counter, and means on said carrier for actuating said counter determined by the presence of an article gripped on said carrier.

12. In a machine of the class described, a gripper carrier, a casing having a receiving 125 mouth, a lip movable on said mouth, a plurality of sets of grippers on said carrier, secondary levers operated by said grippers

- upon an excessive movement thereof, and a counter actuated by said secondary levers when so displaced. 45
13. In a machine of the class described, a carrier, a casing having a receiving mouth, a lip movable on said mouth, means for moving said carrier from said lip, grippers on said carrier, secondary levers displaced by said grippers, studs projecting laterally from said secondary levers, and a counter adapted to be engaged by said studs in certain positions thereof. 50
14. In a machine of the class described, a carrier drum having a drum head, a casing having a receiving mouth, a lip movable on said mouth, means for moving said carrier from said lip, receiving means within said casing, a gripper on said drum, a counter stud projecting laterally over said drum head and displaced by said gripper, and a Geneva wheel coöperating with said drum head and counter stud. 55
15. In a machine of the class described, a gripper drum having a head with a peripheral notch, an actuator for said drum, a gripper on said drum, a counter stud displaced by said gripper, and projecting laterally over said head opposite said notch, and a Geneva wheel coöperating with said head and stud. 60
16. In a machine of the class described, a carrier drum having a drum head, an actuator therefor, a gripper axle extending along the drum, an actuating lever therefor outside of said drum head, a fixed cam coöperating with said lever, a secondary lever having a tappet engaged by said actuating lever, a laterally projecting stud on said secondary lever extending over said drum head, and a Geneva stop wheel coöperating with said stud and drum head. 65
17. In a machine of the class described, a carrier adapted to receive and advance an article, grippers upon said carrier movable in a closing direction beyond normal gripping position, a device for actuating said counter by said carrier, and means for automatically moving said device to inoperative position when the grippers move in a closing direction beyond normal gripping position. 70
18. In a machine of the class described, a feeding drum, an actuator for said drum, a counter, a gripper adapted to clamp the article to be counted upon the drum to cause the article to be advanced with the drum, said gripper when in clamping position establishing an operative connection between the drum and counter. 75
19. In a machine of the class described, a feeding drum, an actuator for said drum, a casing having a mouth adjacent to said actuator and delivering in proximity to said drum, a counter adapted to be actuated by the rotation of said drum, and a connection between the drum and counter whereby the counter is actuated by the rotation of the drum, said connection including a part adapted to engage the article to be counted to position the connection in operative relation to the drum. 80
20. In a machine of the class specified, a carrier provided with grippers, actuating means therefor, an arm pivoted on said carrier to move bodily therewith, a counter adapted to be operated by the said arm, operating means for said grippers, said operating means and arm having co-acting parts adapted to engage and displace said arm when the grippers operate without engagement with an article. 85

Signed at Brooklyn in the county of Kings and State of New York this 11th day of June A. D. 1914.

FREDERICK G. JAHN.
